SPEED GOVERNOR

Original Filed Aug. 12, 1920 2 Sheets-Sheet 2

UNITED STATES PATENT OFFICE.

WILLIAM S. DORMAN, OF BROOKLYN, NEW YORK, ASSIGNOR TO ROSS G. LEONARD,
OF BROOKLYN, NEW YORK.

SPEED GOVERNOR.

Application filed August 12, 1920, Serial No. 403,104. Renewed September 2, 1922. Serial No. 586,023.

To all whom it may concern:

Be it known that I, WILLIAM S. DORMAN, a citizen of the United States of America, and resident of Brooklyn, Kings County, 5 State of New York, have invented certain new and useful Improvements in Speed Governors, of which the following is a specification.

This invention relates to certain improvements in speed governors; and the objects and nature of the invention will be readily understood by those skilled in the art in the light of the following explanation of the accompanying drawings illustrating 10 what I now believe to be the preferred mechanical expression or embodiment of my invention from among other forms, constructions and arrangements within the spirit and scope thereof.

20 An object of the invention is to provide certain improvements in speed limiting devices of the type wherein a speed responsive mechanism, such, as a centrifugal governor, cooperates with a valve to throttle the intake conduit through which the explosive engine or other motor receives its supply 25 of motive fluid, for the purpose of preventing the speed of the motor and consequently the speed of the vehicle, from exceeding a certain predetermined limit for which the 30 device has been set or adjusted.

With these and other objects in view, the invention consists in certain novel features in construction and in combinations and arrangements as more fully and particularly 35 set forth and specified hereinafter.

Referring to the accompanying drawings:—

Fig. 1, is a side elevation showing the device of my invention interposed between the carburetor and intake manifold of a motor vehicle.

Fig. 2 is a detached perspective view of the device of my invention, a portion being broken away.

Fig. 3 is a horizontal longitudinal section of the structure shown by Fig. 2, taken along horizontal lines to show the valve in top plan, and to show the housing and centrifugal governor in central longitudinal section.

Fig. 4 is a cross section on the line 4—4, Fig. 3.

Fig. 5, is a detail perspective, the valve

and centrifugal governor controlling spring 55 being indicated by dotted lines.

Fig. 6 is a detail cross section through a portion of the valve and its seat.

Fig. 7 is a section on the line 7—7, Fig. 3.

In the particular embodiment of my invention disclosed, I provide a valve casing 1 constructed and arranged to be included in the intake conduit and to form and constitute a portion of said conduit. In this instance, I show a casing secured to the carburetor 2 and the intake manifold 3, and interposed between said parts, although I do not wish to so limit my invention.

In this instance, I show the valve casing (considered as a whole) formed with inlet 70 port *a* through its bottom wall, and outlet port *b* through its top wall and alined with port *a*. The port *a* is alined and registers with the carburetor outlet, and the port *b* with the manifold inlet, and the casing is 75 fitted between, and usually conforms to the flanges of the necks of the carburetor and manifold, and (in this instance) is shown secured thereto by the bolts 4 passing through said flanges and the casing and 80 thereby clamping the carburetor and manifold necks to the casing to form intervening tight joints, and providing a direct passage through the casing from carburetor to manifold. It is in this passage that the 85 throttle valve is located.

The casing is formed with suitable annular top and bottom seats or faces around the ports *b*, *a*, to fit the flanges of the manifold and carburetor, while the casing walls 90 have thickened or elongated opposite ends through which vertical holes 4^a extend to receive the clamping bolts 4. The casings can be provided in standard shapes and sizes to fit the standard carburetor and manifold 95 neck flanges and intervening spaces, and hence the casings can be readily assembled with the carburetors and manifolds and secured by the bolts 4 such as usually employed for securing the carburetors and manifolds. 100

I show a throttle valve of the rotary or shutter type, in this instance, comprising a flat circular stationary disk 5, forming the valve seat, and an approximately similar flat circular disk 6 resting against and parallel 105 with disk 5 and mounted to rotate on a center vertical axis and forming the valve element.

The valve seat is formed with a center

hub 5^a and an annular rim 5^b, and the valve is likewise formed with a center hub 6^a and an annular rim 6^b. The bores of the two hubs are alined and the hubs abut end to end, and the rims also abut at their meeting side faces. The valve is confined to the seat by center screw 7 which constitutes the axis on which the valve is rotatable, and if so desired, the screw can be adjustable to regulate the fit or tension between the valve and its seat.

The valve and seat are of the grill or shutter type to secure quick maximum opening and closing by a slight or short movement. For instance, the annular portions of both the seat and valve between the hubs and rims are composed of radial bridges 5^c, 6^c, and intervening radial slots or slits 5^d, 6^d. The bridges and slits of the seat correspond to the bridges and slits of the valve, so that when the valve slits register with the seat slits and the valve bridges with the seat bridges, the valve is in maximum open position for passage of the full motor charge through the conduit. When the valve bridges overlie and cover the slits of the seat, such slits are approximately closed against passage of motor charge and the valve is in maximum closed position, and when the valve is in intermediate positions more or less throttling is attained, as will be readily understood by those skilled in the art. Of course, those skilled in the art understand that when the valve is in said closed position, there is, as a rule, provision for passage of just enough motor charge (combustible mixture) to keep the motor at least turning over so that the motor can promptly pick up again when the vehicle speed is properly reduced and the valve again opened.

The valve and its seat span and control the conduit through the casing and in order to permit location of these elements in and their removal from the casing, said casing is provided with a separately formed annular end 1^a fitted and secured to the casing body, the valve and its seat being interposed between said body and said end. In the example illustrated, the body 1 is annularly and internally rabbeted or recessed to receive the rims of the valve and its seat and to provide annular shoulder 1^b to which the rim of the valve is confined by the seat. The rim of the seat is formed with a flange 5^e and said seat and its flange are countersunk in the body 1 and removably secured by suitable means such as one or more machine screws 5^f. The casing end is secured to the casing body by suitable means, such as screws 1^c, and in the finished casing these screws are usually concealed by solder.

In assembling, the valve and its seat are secured together by the axis or pivot screw 7, and thereafter are handled as a unit when

being located in the casing, and then concealed from the exterior of the casing by the casing end 1^a. The pivot screw 7 is usually provided with a slotted end head accessible through the port 6 before the casing is secured to the manifold or carburetor (or by detaching the casing) for adjusting the valve toward or from its seat.

The valve casing carries the centrifugal governor or speed responsive device and operative connections therefrom to the valve.

For instance, I show the valve casing formed integral with an extension in the form of an elongated straight housing or tubular guide 8, arranged exteriorly and to one side of the casing, approximately tangentially with respect thereto and projecting in opposite directions therefrom.

The reciprocatory valve stem is longitudinally arranged within this housing, and the centrifugal governor is arranged in an appropriate chamber located at one end of said housing, the other end of the housing being open and provided with suitable closures normally closing the same.

In this instance, the valve stem comprises two alined abutting sections or rods 9, 9^a. The stem section 9 is operatively connected to the valve through the medium of a rigid lateral arm 9' normally fixed with respect to said stem section, and a wrist pin 6^e rigid with and rising from the valve at a point between the hub and rim of the valve. The arm 9' is formed with a longitudinal slot or socket receiving the pin for operatively joining the pin and arm. In this particular instance, this slot or socket is formed by the bifurcated end 9'' of the arm.

In this example, the lateral arm 9' is formed by a piece separate from the stem and provision is made for relative adjustment whereby the position of the arm longitudinally of the stem can be varied. I hence show the outer end of the arm formed with a nut or hub 9^g having a screw threaded bore through which the longitudinally threaded portion 9^h of the stem extends. After the stem and arm have been adjusted to the desired position, the parts can be locked together by set screw 10, accessible through a hole 10' in the tubular housing (Fig. 4).

The nut or hub 9^g in this instance, also serves as an abutment on the valve stem, for the inner end of the valve spring 11.

A hollow nut 12 receives the outer end of the spring and forms the abutment for said end.

The open outer end of the housing is internally threaded to receive said nut and to permit longitudinal adjustment thereof to vary the tension of the spring on the valve. This nut projects from the housing end and its outer end is formed to receive a suitable nut-rotating tool. The nut is formed with

a longitudinal bore opening through its outer end, and the outer end of the stem 9, reciprocates in and is guided by this bore and projects outwardly beyond the same. The 5 projecting outer end of the stem is preferably formed to receive a suitable tool by which the stem can be rotated to adjust the arm 9'.

I preferably enclose the outer ends of the 10 nut 12 and stem by a removable cap 13, screwing exteriorly on the projecting end of the nut. The ends of the cap and housing are preferably formed to provide for a tight joint between their meeting faces and to permit application of a seal, after the proper 15 adjustments have been effected and the parts have been so set.

The valve operating arm 9' of the valve stem, extends through and moves in a horizontal 20 elongated slot 14 in the wall of the casing 1 intervening between the interiors of the casing 1 and its extension 8. This slot is comparatively narrow to confine the arm to its path of movement parallel with 25 the plane of the valve and to hold the nut 9' of the arm against rotation with the stem.

At its other end, the casing extension or 30 housing 8, carries the governor and provides the governor compartment or chamber. This compartment is formed by a circular exterior end wall or head 14 integral with the housing 8 having a cylindrical flange 14', and a bell or cup-shaped housing 15, longitudinally fitting the flange 14' and (in 35 this instance) removably secured thereto by a screw threaded connection. Within the compartment, the end of housing 8 forms a boss or journal 8' having an exterior longitudinal cylindrical surface.

40 The housing 8 is formed with a longitudinal bore 8' extending through the boss 8' and this bore serves to guide the inner end of stem section 9, and receives and guides stem section 9'.

45 The stem section 9' is formed with a stop head 9' within the governor compartment and opposite and adapted to abut the end face of the boss 8'. The section 9' forms a push stem with its end within the housing 50 8 arranged to abut the adjacent end of stem section 9, to force the valve on closing movement.

The parts are so arranged that spring 11 55 constantly acts on the stem to yieldingly hold the valve in full open position, and the stem stop head 9' at its limit of movement (to the right Fig. 3) away from the end face of the boss 8'.

A centrifugal governor is provided in 60 the governor compartment, to act on the stem stop head 9' and force the same toward the bearing boss end face and consequently move the valve on throttling stroke through the medium of the valve stem, when the

speed of the motor or of the vehicle exceeds 65 the limit for which the governor is set.

The governor comprises and is carried and driven by a hollow spindle 16 longitudinally arranged in the governor compartment in alignment with the longitudinal axis of the 70 valve stem and cylindrical surface of boss 8'. The bearing boss extends longitudinally into this spindle which rotates on the cylindrical outer surface thereof and is centered and its inner end is supported thereby. 75

The inner end face of the hollow spindle 16 abuts the side face of the wall 14 to limit longitudinal movement of said spindle toward said wall. Longitudinal movement of the spindle in the opposite direction (outwardly) is limited by the engagement of an 80 annular shoulder 16' of the spindle with an opposing annular shoulder of the governor housing formed by the outer end wall of said housing, where said housing contracts to 85 form the central longitudinally projecting hollow neck or nipple 15'. This projecting neck provides a longitudinal bearing for the reduced cylindrical outer journal end 16' of the governor spindle. The reduced 90 journal end 16' of the spindle is formed with a longitudinal socket 16', angular in cross section, and an air tight wall is provided between this socket and the interior of the spindle to prevent air leakage. The socket 95 16' is formed to removably receive the angular rotary drive shaft end 17 whereby the governor is driven. This drive shaft extends longitudinally into the housing neck 15' through the reduced bearing bore there- 100 in and is driven in any suitable manner or by any suitable means, for instance, by flexible shafting from any rotary member driven by the motor or by any rotary portion of the vehicle, as will be understood by 105 those skilled in the art.

The driving means for the governor is arranged to rotate the governor at a known proportionate or scaled speed with respect to the R. P. M. of the motor, a propeller, or 110 with respect to the travel of a vehicle.

The governor embodies an outer side circular disk 18 forming a head surrounding and fixed to the spindle 16 and consequently 115 rotating therewith, and a corresponding opposing inner side rotary head movable longitudinally of said spindle and formed by a circular disk 19 spaced from and arranged between fixed head 18 and the casing wall 14. The movable head 19 is fixed to a hub or sleeve 19' surrounding, longitudinally 120 slidable on and rotating with the spindle 16.

The hub 19' is confined to rotate with the spindle through the medium of a cross-member such as a pin 19' at its ends fitted in perforations in the hub and diametrically spanning its bore and consequently diametrically spanning the bore or interior 125

chamber of the spindle. Longitudinal movement of the hub on the spindle is provided for by diametrically opposite longitudinal slots 16^a in the spindle and through which 5 the pin extends and in which it is movable longitudinally of the spindle. The impelling weights of the centrifugal governor are formed by an annular ring or series of loose balls 20 surrounding the hub 19^a and 10 arranged between the adjacent parallel flat side faces of the two heads 18, 19.

The annular edge or rim portions *e* of these two heads are tapered or flared in opposite directions so as to converge and therefore 15 by form the annular balls space or chamber between the heads with an annular circumferential contracted rim and oppositely wedging annular cam faces formed by the inner or adjoining surfaces of the flared or 20 tapered rim portions *e*.

These flared rim portions are so formed that the outward pressure of the balls on said portions *e* (when the balls are thrown radially by centrifugal force under excessive 25 speed of the governor) will exert pressure on the two heads longitudinally of the centrifugal axis of rotation and consequently will force the movable head 19 toward the valve stem.

30 The pin 19^b extends diametrically across the interior chamber of the spindle outwardly beyond the end face of the spindle bearing boss 8^a and also outwardly beyond the stop head 9^e of the valve push stem. This 35 pin 19^b is utilized as the operative connection between the governor and the valve push stem. When the speed of the governor is excessive (is beyond the R. P. M. for which the governor has been set) the outward 40 pressure of the balls on the flared rims of the governor will force the movable head 19, consequently the pin 19^b toward the left (Fig. 3) and the pin contacting with the valve stem head 9^e will force the valve stem 45 50 toward the left to move the valve on its throttling stroke against the tension of its spring 11. This spring serves to return the governor to normal position (through the medium of the valve stem) as well as to return the throttle valve to normal position.

The spring 11 is adjusted so that its tension will hold the throttle valve in open position under such force that the governor will not move the valve from such position unless 55 and until the R. P. M. of such governor exceeds a certain predetermined limit. For instance, speed limiting devices are usually adjusted when applied to commercial vehicles, to automatically throttle down the 60 motor when the speed of travel of the vehicle exceeds twelve miles an hour, more or less, or when the speed of the motor exceeds a certain number of R. P. M. This limit in my device is fixed and determined 65 by the tension or pressure of the valve

spring on the valve. The governor must reach a certain speed to generate the necessary power through its weights to force back the spring and move the valve on its throttling stroke. 70

Each speed limiting device is set or adjusted, to suit the particular motor to which it is to be applied, i. e., according to motor type, horse power, operating speed, etc. I 75 ordinarily form the slit or slot ports in the valve and its seat so that the total maximum capacity thereof is sufficient to supply motive fluid for high speed and horse power motors at their maximum speed. By rotation of stem 9 and adjustment of the 80 spring, I can set the position of the valve at normal operation through arm 9', to suit the particular motor to which the device is applied, and also control the limit of closing or throttling movement of the valve. 85

Motors of different makes require throttled inlets of different capacities to insure sufficient fuel to keep the motors slowly turning. Hence, one motor will require a different throttling limit for the throttling valve from that required by another motor. The cross member 19^b of the governor has an approximately fixed normal position and path of movement longitudinally of the 90 governor and the engagement of the valve stem head 9^e with said pin limits the opening movement of the valve while the engagement of said head 9^e with the end of boss 8^a limits the closing movement of the valve. 95

It will be noted that the governor is first assembled, and then as a unit placed in the bell-shaped housing. The housing then carries the governor and it can be thus applied to and removed from the casing. The push stem 9' is placed in the casing through the bore in the bearing boss 8^a, before the bell shaped housing carrying the governor, is applied to the casing. 100 105

It will be noted, that the casing can be assembled with the manifold and carburetor, with either port *a* or *b*, uppermost, or with the governor located at either the right or left hand (Fig. 3), particularly as it makes no difference in the operation of the valve whether it is above or below its seat, or in fact, whether the valve and its seat are arranged horizontally or vertically. 110 115

It is evident that various changes, modifications and variations might be resorted to, that features might be added and parts omitted, without departing from the spirit and scope of my invention, and hence I do not wish to limit myself to the exact disclosures hereof. 120

What I claim is:—

1. A speed limiting device comprising a valve casing at one end having a longitudinally-projecting boss with an exterior cylindrical bearing surface, a throttling valve movable in said casing to control the motive 125 130

- fluid passage therethrough, a spring in the casing normally holding said valve in open position, a housing removably secured to the end of the casing having said boss, a centrifugal governor within said housing and removable therewith, said housing providing a bearing for said governor, said governor also removably fitting and rotating on said boss, the outer end of said housing having a longitudinal bearing opening for the reception of driving means for said governor, and means extending through said boss for operatively connecting the governor and valve. 70
- 15 2. A speed limiting device comprising a valve casing having a projecting boss with an exterior cylindrical bearing surface, a spring-held throttling valve in the casing, a stem movable through said boss for forcing the valve on its throttling movement, a housing removably secured to the casing, a centrifugal governor arranged in and removable with said housing and embodying a rotary spindle having a hollow end removably receiving and rotating on said boss, the outer end of said housing providing a bearing in which the outer end of said spindle is confined, said spindle formed to receive driving means, said housing having an opening for the reception of said driving means, said centrifugal governor being operatively arranged with respect to said stem to actuate the same. 80
- 20 3. A speed limiting device comprising a valve casing at one end providing an exterior cylindrical bearing surface, a throttling valve in said casing, a housing on said casing end and removably confined thereto and at its outer end provided with a longitudinal bearing and a bore opening through the housing end in longitudinal continuation of said bearing, and a centrifugal governor arranged to actuate said valve on its throttling stroke, said centrifugal governor being confined in and carried by said housing and embodying a rotary spindle at its outer end confined in said housing bearing and at its inner end removably fitting said cylindrical bearing surface, the outer end of said spindle in alinement with said bore being formed to removably receive centrifugal governor driving means entering through said bore. 85
- 25 4. A speed limiting device comprising a valve casing at one end having a boss with an exterior cylindrical bearing surface, a throttle valve in said casing, a housing removably confined to the casing with said boss projecting into the housing, and a centrifugal governor confined within and removable with said housing and arranged to control said valve and embodying a rotary longitudinal spindle having a hollow end removably receiving and centered on said boss and at its other end confined and mounted in the outer end of said housing, said spindle formed to receive driving means, said housing formed with a bore for the passage of said driving means from the exterior of the housing to said spindle. 90
- 30 5. A speed limiting device comprising a valve casing at one end having an exterior cylindrical bearing surface, a throttle valve in said casing, a housing forming a centrifugal governor compartment at said end of the casing and at its outer portion formed with a longitudinal reduced bearing, said housing having a bore for the entrance of governor driving means, and a centrifugal governor arranged in said housing in operative actuating relation to said valve, said governor embodying a rotary spindle formed to operatively receive said driving means, one end of said spindle longitudinally fitting said cylindrical driving surface and arranged to abut the adjacent casing wall, the opposite end of said spindle reduced to fit in said bearing and to form an annular shoulder to abut the adjacent housing wall. 95
- 35 6. A speed limiting device comprising a valve casing at one end having a boss with a cylindrical bearing surface, a throttle valve in said casing, a housing at said end of the casing providing a spindle bearing and also providing for the entrance of driving means to said spindle, a centrifugal governor in said housing, said centrifugal governor embodying a spindle mounted in said bearing and having a hollow end centered on said boss, centrifugal weights, means actuated by said weights and extending into said hollow end and movable longitudinally thereof, and actuating means for said valve movable through said boss and extending into said hollow end into operative relation with said means actuated by the weights. 100
- 40 7. A speed limiting device comprising a casing forming a conduit, a rotary throttle valve spanning the conduit with its axle of rotation within and arranged longitudinally of the conduit, said valve having a wrist pin projecting from its side face between the valve axis and its periphery, said casing having an exterior extension arranged beside the same, the casing projecting laterally from the extension, a housing carried by one end of the extension, a centrifugal governor in the housing, and a spring pressed reciprocatory push rod connection in line with the governor axis and longitudinally within said extension and located outside of said conduit and provided with a lateral arm projecting therefrom to a point beside said valve and into operative engagement with said wrist pin, said push rod connection having operative relation with the governor and operating and controlling the position of said valve, means being provided for setting the valve with respect to said push rod connection to vary the opening and 105
- 45 8. A speed limiting device comprising a valve casing at one end having a boss with an exterior cylindrical bearing surface, a throttle valve in said casing, a housing removably confined to the casing with said boss projecting into the housing, and a centrifugal governor confined within and removable with said housing and arranged to control said valve and embodying a rotary longitudinal spindle having a hollow end removably receiving and centered on said boss and at its other end confined and 110
- 50 9. A speed limiting device comprising a valve casing at one end having a boss with an exterior cylindrical bearing surface, a throttle valve in said casing, a housing removably confined to the casing with said boss projecting into the housing, and a centrifugal governor confined within and removable with said housing and arranged to control said valve and embodying a rotary longitudinal spindle having a hollow end removably receiving and centered on said boss and at its other end confined and 115
- 55 10. A speed limiting device comprising a valve casing at one end having a boss with an exterior cylindrical bearing surface, a throttle valve in said casing, a housing removably confined to the casing with said boss projecting into the housing, and a centrifugal governor confined within and removable with said housing and arranged to control said valve and embodying a rotary longitudinal spindle having a hollow end removably receiving and centered on said boss and at its other end confined and 120
- 60 11. A speed limiting device comprising a valve casing at one end having a boss with an exterior cylindrical bearing surface, a throttle valve in said casing, a housing removably confined to the casing with said boss projecting into the housing, and a centrifugal governor confined within and removable with said housing and arranged to control said valve and embodying a rotary longitudinal spindle having a hollow end removably receiving and centered on said boss and at its other end confined and 125
- 65 12. A speed limiting device comprising a valve casing at one end having a boss with an exterior cylindrical bearing surface, a throttle valve in said casing, a housing removably confined to the casing with said boss projecting into the housing, and a centrifugal governor confined within and removable with said housing and arranged to control said valve and embodying a rotary longitudinal spindle having a hollow end removably receiving and centered on said boss and at its other end confined and 130

closing limits of the valve by adjusting said arm longitudinally of said push rod connection.

8. A speed limiting device comprising a casing forming a conduit, a rotary throttle valve and its seat spanning the conduit with the axis of rotation of the valve arranged longitudinally of the conduit, said casing having an exterior tubular extension arranged beside the same with the casing projecting laterally from the extension, a centrifugal governor carried by the extension, a spring pressed reciprocatory push rod connection in line with the governor axis and arranged longitudinally within said extension, and means coupling said connection to the valve at a side face thereof to operate and control the position of the valve, said connection being constantly held in operative contact with a moving part of the governor to limit the opening movement of the valve, said connection having a head to engage a shoulder of the extension to limit the closing movement of the valve, means being provided for varying the relative position of the valve with respect to said connection for adjusting the limits of opening and closing movements of the valve.

9. A speed limiting device comprising a casing forming a conduit, a rotary throttle valve spanning the conduit with its axle of rotation within and arranged longitudinally of the conduit, said casing having an exterior extension arranged beside the same, the casing projecting laterally from the extension, a housing carried by one end of the extension, a centrifugal governor in the

housing, and a spring pressed reciprocatory push rod connection in line with the governor axis and longitudinally within said extension and located outside of said conduit and provided with a lateral arm projecting therefrom to a point beside said valve and operatively connected thereto, said push rod connection having operative relation with the governor, means being provided for setting the valve with respect to said push rod connection to vary the opening and closing limits of the valve by adjusting said arm longitudinally of said push rod connection.

10. A speed limiting device comprising a casing forming a conduit, a rotary throttle valve and its seat spanning the conduit with the axis of rotation of the valve arranged longitudinally of the conduit, said casing having an exterior tubular extension arranged beside the same with the casing projecting laterally from the extension, a centrifugal governor carried by the extension, a spring pressed reciprocatory push rod connection in line with the governor axis and arranged longitudinally within said extension, and means extending laterally from said connection and operatively coupling said connection to the valve to rotate and control the valve, said connection being constantly held in operative contact with a moving part of the governor to limit the opening movement of the valve, said connection having a head to engage a shoulder of the extension to limit the closing movement of the valve.

WILLIAM S. DORMAN.
